LUBRICATED HIGH SPEED RINGS AND TRAVELER FOR TWISTER FRAMES

James R. Mulholland, University Heights, Ohio

Application December 26, 1956, Serial No. 630,501

19 Claims. (Cl. 57—120)

This invention relates to textile rings and more particularly to novel means for lubricating the traveler of said textile rings.

It is an object of the present invention to provide a textile ring having an oil reservoir integrally associated with said ring and removable together with said ring from a supporting rail and means for accurately controlling leak-proof flow of lubricant, to the traveler associated therewith.

Another object of the present invention is to provide a textile ring with novel means for allowing the traveler associated therewith to seek its own bearing surface or orbit.

A further object of the present invention is to provide a textile ring having a lubricant channel formed on the inner face of the ring and having means arranged within said channel which are responsive to engagement by the traveler as it travels around the ring in such a manner that the speed of the traveler will influence and control the minute quantities of lubricant being transferred to the traveler from the lubricant channel.

Still another object of the present invention is to provide a textile ring having novel means associated therewith whereby a controlled supply of lubricant is made available to the traveler throughout its circuit path in such a manner that the traveler and ring will be maintained substantially free from lint.

Still another object of the present invention is to provide a textile ring which may be readily adapted for cooperation with a plurality of different size holes provided in a rail support, and further to provide a rail assembly which permits separate maintenance of the individual textile rings.

Another object of the present invention is to provide a textile ring characterized by its structural simplicity, the ease of assembly of its parts, its strong and sturdy nature and its low manufacturing cost. Other features of this invention reside in the arrangement and design of the parts for carrying out their appropriate functions.

Further objects of the present invention and certain practical advantages will be referred to in or will be evident from the following description of one embodiment of the invention, as illustrated in the accompanying drawings, in which:

Fig. 1 is a top plan view of a textile ring mounted on a supporting textile rail made in accordance with the present invention;

Fig. 2 is a vertical sectional view taken along the plane of line 2—2 of Fig. 1;

Fig. 3 is an enlarged fragmentary sectional view showing the position of the traveler and the details of the lubricant channel and wick arrangement in the ring;

Fig. 4 is an enlarged fragmentary sectional view of the ring showing the position of the traveler in operation and the details of the traveler's affect upon the bearing liner provided on the inside of the rail.

Before describing in detail the herein disclosed embodiment of the invention, it is to be understood that the

present invention is not limited to the structural details or the particular arrangement of parts herein shown, as devices embodying the present invention may take other forms. It also is to be understood that the phraseology and terminology herein used are for purposes of description and not of limitation, as the scope of the present invention is denoted by the appended claims.

Textile rings currently used have proven themselves unsatisfactory because of the leakage of lubrication which causes the ruination of the cotton thread and spoilage of the spools being wound. Different ways of lubricating the rings and their associated travelers have been attempted and one of the most recent consisted of providing an elongated lubricated reservoir at the underside of the supporting rail with a plurality of lubricant conduits leading from the reservoir to a like number of textile rings wherein each ring is provided with a lubricant chamber above the level of the lubricant in the reservoir. This method has proven unsatisfactory because it required the removal of all of the textile rings which were rigidly mounted in the apertures provided in the rail, in order to service one or more of the rings. By so manipulating the rail, the reservoir was repeatedly turned sideways or even upside down and leakage of the lubricant upon the thread resulted. In the present invention, I have illustrated my novel textile ring 10 removably mounted on a rail section 11. It will be understood that the rail is provided with a plurality of textile rings 10. The rings are spaced along the length of the rail and the top of the rail is apertured as at 12 directly below each ring. Each ring 10 is provided with its own reservoir 13 which is die cast as an integral part of the ring itself.

As seen in Fig. 2, the textile ring 10 is supported above the plane of the rail 11 in alignment with the aperture 12, by means of three circumferentially spaced bolts 14 which extend downwardly through the reservoir 13 and are connected to the top of the rail by means of nuts 15. Suitable cylindrical spacing elements 16 of desirable length support the ring at the desired height above the aperture in the rail 11. Heretofore the rings 10 were rigidly secured within the aperture 12 and thereby necessitated that the rings and apertures have complementary diameters in order for the ring to be retained within the aperture. It will be readily observed through the provisions of the present invention that the standard ring 10 may be used in connection with various size apertures. As viewed in Fig. 2, it will be readily appreciated that the aperture 12 may be somewhat smaller or somewhat larger than that shown in Fig. 2 while the ring is suspended thereabove, as shown in Fig. 2, by means of the nuts, bolts and spacers.

Preferably, the reservoir 13 is of rectangular cross section and its length is such as to extend circumferentially about the entire periphery of ring 10. The top wall of the reservoir is furnished by a suitable annular plate 13a which is retained thereon by means of the bolts 14 or by any other suitable means. A segment 17 of the reservoir 13 (preferably a quadrant segment thereof) is partitioned off from the rest of the reservoir 13 by means of partition walls 18 and 19. The segment partitioned off is adapted to receive a lubricant absorbing packing 20, such as dental packing, as seen in Figs. 2 and 3, while the remainder of the reservoir is adapted to contain a free lubricant.

The ring 10 is preferably made from a steel forging and is case hardened after machining. The ring and its integrally formed reservoir may be turned from one piece of metal by using two forming tools. Prior to hardening the ring it is machined at its inner diameter to provide a reentrant channel or chamber as indicated at 22, see Figs. 2, 3 and 4.

A phosphorous bronze bearing liner 23 is placed in the channel 22 so that the inner diameter of the bearing liner 23 is not flush with the inner face of the ring 10 but rather lies in a plane which extends radially beyond the plane of the inner face of the ring 10 in such a manner that the inner face of the bearing liner 23 lies somewhat within the channel 22 and provides offset shoulders 24 and 25 with the inner face of the ring, as seen in Fig. 4. The channel 22 has a depth substantially greater than the thickness of the liner 23 and provides a lubricant chamber 26 behind the liner 23. The liner 23 is an imperforate annular member proportioned to have a close fit at the upper and lower edges of the channel 22. The liner 23, however, is not bonded or permanently secured to the body of the ring and the lubricant from the chamber 26 is advanced to the interior of the ring at the upper and lower edges of the liner 23. A tubular lubricant wick 27 made of a cotton fabric sometimes referred to as "sleeving" is arranged behind the liner 23. The tubular wick 27 is cut so that its ends abut each other to form an annular tubular member which encircles and abuts the rear surface of the liner 23. A second supply wick 28 of smaller diameter extends approximately $\frac{1}{4}$ " into the chamber 26 behind the tubular wick 27 in contact with the rear surface of said wick 27. The wick 28 is threaded through a suitable passage or conduit 29 provided in the side wall of the ring 10 extending laterally and downwardly between the channel 22 and reservoir 13. The wick 28 extends into the quadrant portion 17 of the reservoir where it is coiled, as seen in Fig. 1, about packing 20. A third wick which may be called a feeder wick 28a is coiled about packing 20 but in no way contacts supply wick 28, and then passes through a small groove 13b provided in the under surface of plate 13a and into the remainder of the reservoir which contains free lubricant. As seen in Fig. 1, the wick 28a extends throughout the length of said free lubricant containing portion of the reservoir, however, it need not be this long. With the arrangement described above, it will be understood that wick 28a extending into the free lubricant containing portion of the reservoir supplies lubricant to the packing 20. Wick 28 communicates lubricant between the packing 20 and the tubular lubricant wick 27 in channel 22. It will be understood that wick 28 supplies lubricant only upon demand or requirement of lubricant by the tubular wick 27. Feeder wick 28a supplies only a limited amount of lubricant to packing 20 which in turn feeds lubricant to supply wick 28 when needed by tubular wick 27.

As the tubular wick 27 is flattened by the liner 23 a certain amount of lubricant is released thereby and escapes at the upper end lower edges of the liner 23. Through the provision of packing 20, it will be understood that lubricant will not be supplied as quickly to the tubular wick 27 as it would if the wick 28 fed directly into a free lubricant area of the reservoir just prior to its contact with tubular wick 27. The packing 20 therefore tends to limit the flow of lubricant to the tubular wick 27 and thereby limits the total quantity of lubricant flowing. It also limits the flow of lubricant to only those periods when lubricant is needed. This occurs only after the tubular wick has been squeezed or flattened by the liner 23 and a portion of the lubricant contained therein has been forced outwardly via the upper and lower edges of the liner 23. Lubricant is, of course, introduced into the channel 22 by capillary action of the wick 28. The provision of the packing 20 is also an important factor in maintaining a uniformity of lubricant flow to the tubular wick 27.

The ring 10 provides a body having an upper rim 30 which is adapted to be embraced by the upper hook 31 of a traveler 32 and a lower rim 33 adapted to be embraced by the lower hook 34 of the traveler. It will be noted that the radius of the upper rim 30 is larger than the radius of the lower rim 33. Furthermore, the vertical

center line 35 of the lower rim 33 lies radially (with respect to the ring 10) outside of a vertical center line 36 of the top of the upper rim 30.

The upper hook 31 of traveler 32 has an enlarged U-shape the base portion of which extends at substantially right angles to the shank portion 37 and the outermost arm 38 extends substantially parallel to the shank portion 37 and at right angles to said base portion. The lower hook of the traveler 32 is also of U-shape but substantially smaller than the upper hook portion 31. It will be noted that the shank portion 37 is bent radially inwardly at 40 whereby the upper portion of the traveler tilts radially inwardly of the ring 10. The traveler 32, of course, is influenced by the pull from a thread member 41 which engages its upper hook portion 31 and causes the traveler to tilt radially inwardly at the top and to further seek a bearing surface for its bottom hook portion. The bearing surface or fulcrum provided at the bottom actually consists of two point contacts, namely 42 and 43. The arm 38 of the upper hook 31 of the traveler rides in point contact at 44 with the outer surface of the upper rim 30 of the textile ring 10, as seen in Fig. 3. Stroboscopic examination of the ring while running indicates that the traveler shank contacts the ring and bearing liner 23 substantially as illustrated in Fig. 4 and it is believed that oil picked up by the shank of the traveler is conducted downwardly on the traveler to the points of contact 42 and 43.

The precise way in which lubricant is transferred from the tubular wick 27 behind the bearing liner 23 to the traveler 32 is not definitely understood at the present time. It is believed, however, that as the traveler 32 travels around the ring, the shank portion 37 thereof, due to centrifugal force exerts a pressure against the liner 23, as seen in Fig. 4. With reference to Fig. 4, it will be noted that the bend 40 in shank 37 contacts the inner surface of the ring 23 at point 43, just below the channel 22. As the traveler is carried around the ring, centrifugal force acts upon the traveler to carry the central shank portion thereof radially outwardly causing it to bear upon the liner 23 so as to deflect or move the liner 23 against the tubular wick 27 functioning somewhat as a diaphragm pump so that minute quantities of lubricant are squeezed or transferred outwardly via the upper and lower edges of liner 23. It will be noted that the shoulders 24 and 25 of the channel 22 provide bearing supports for the shank portion of the traveler in such a manner that only the portion of the shank of the traveler intermediate said shoulders contacts the liner 23, thereby providing a space between the shank's point of contact with the bearing liner and the shoulders 24 and 25. Due to the speed of the traveler, the lubricant, which is preferably composed of oil and an easily evaporating oil soluble agent of any suitable type, is atomized. The oil soluble agent evaporates and the oil flows onto the traveler and is carried to the points of contact, as heretofore explained. It is further believed that a vacuum is formed by the high speed traveler (which travels at speeds in excess of 5,000 feet per minute) in the space between the traveler 32, bearing liner 23 and shoulders 24 and 25 as seen in Fig. 4. This action deposits only the amount of lubricant necessary to lubricate the points of contact 42 and 43 between the traveler and the ring 10 and prevents fugitive lubricant from being deposited on the thread 41 as it travels through the upper hook end portion of the traveler 32.

The present construction provides an additional advantage in removing lint from the traveler and thread. With reference to Fig. 2, it will again be noted that the ring 10 is maintained above the plane of the top portion of the supporting rail 11 and aperture 12. A current of air is created and forced upwardly through the aperture 12 of the support rail in present spool winding operation, in previous constructions the ring was rigidly secured within the aperture 12 to the top of the support

rail 11, the air of necessity had to travel upwardly through the central portion of the ring. However, with the present construction, the high speed travel of the traveler as it moves around the ring 10 sets up an air current which causes the incoming air to deflect at right angles along the path shown by arrows 47, see Fig. 2, which take a radially outwardly course through the space provided between the bottom of the ring 10 and the top of the rail 11. Thus, the lint content within the area of the center of the ring 10 is substantially reduced. As the thread 41 is fed downwardly, at an angle as seen in Fig. 2, the traveler 32 as it moves about a ring 10 causes the thread to form a cone which sets up air currents in the direction of arrows 48. The air currents 48 further aid in removing the lint laden air away from the present operating mechanism.

From the foregoing, it will be understood by those skilled in this art that the present invention is adapted for use with standard textile frames having channel-shaped rail sections. No modification is required of the rail or other parts of the frame and the present rings may be used in connection with a rail having a plurality of apertures, which may be of varying size. For mounting the present rings in the standard rail, it is only necessary to drill a few holes for the bolts 14 and then mount the bolts and their associated spacers 16 and nuts 15 in such a manner that the ring is supported above the aperture in the rail.

In view of the foregoing description, taken in conjunction with the accompanying drawings, it is believed that a clear understanding of the construction, operation and advantages of the device will be quite apparent to those skilled in this art.

Having thus described my invention and illustrated its use, what I claim as new and desire to secure by Letters Patent is:

1. A textile ring having an upper rim adapted to be embraced by the upper hook of a traveler and a lower rim adapted to be embraced by the lower hook of a traveler, said ring having a reentrant lubricant channel opening into the inner face of said ring, an imperforate liner mounted in said channel, said imperforate liner having an inner diameter somewhat larger than the inner diameter of said ring, the inner face of said liner residing within said channel and forming offset shoulders with the inner face of said ring, said liner having a thickness less than the depth of the channel to provide a chamber in back of said liner, a tubular wick in said chamber substantially filling the same and being in contact with said liner, a lubricant reservoir associated with said ring having a quantity of lubricant disposed therein, said ring having a bore leading from said chamber in back of said liner to said reservoir, wick means extending through said bore having one end thereof in the lubricant of said reservoir and the other end thereof in communication with said tubular wick contained in said chamber in back of said liner, said wick means providing a constant lubricant supply to said tubular wick contained in said chamber in back of said liner, and said liner being actuatable by said traveler to cause said tubular wick to provide a predetermined quantity of lubricant to said textile ring.

2. The combination of claim 1 wherein said reservoir is formed integrally with said ring, said reservoir extending circumferentially around the periphery of said ring, said wick means including packing means provided in said reservoir.

3. The combination of claim 1 wherein said reservoir is formed integral with the material of said ring, said reservoir extending circumferentially around the periphery of said ring, the bottom of said reservoir having a level below that of said channel provided in the interior face of said ring, and the top of said reservoir having a level above the bottom of said channel, and said wick

means including packing means provided in said reservoir.

4. A textile ring having an upper rim adapted to be embraced by the upper hook of a traveler and a lower rim adapted to be embraced by the lower hook of a traveler, said ring having a reentrant lubricant channel opening into the inner face of said ring, an imperforate liner mounted in said channel, said imperforate liner having an inner diameter somewhat larger than the inner diameter of said ring, the inner face of said liner residing within said channel and forming offset shoulders with the inner face of said ring, said liner having a thickness less than the depth of the channel to provide a chamber in back of said liner, a tubular wick in said chamber substantially filling the same and being in contact with said liner, a lubricant reservoir extending circumferentially around the exterior of said ring having a quantity of lubricant disposed therein, a wick extending into said reservoir and providing a constant lubricant supply to said tubular wick contained in said chamber in back of said liner, and means on said traveler for actuating said liner and tubular wick to cause a predetermined quantity of lubricant to flow to said textile ring.

5. The combination of claim 4 wherein said lubricant reservoir is provided with a segmental portion which is divided from the remainder of said lubricant reservoir, packing means contained in said segmental portion, a bore between said segmental portion and the remainder of said lubricant reservoir containing free lubricant, and a feeder wick having one end portion thereof extending into said free lubricant and the other end thereof communicating with said packing means.

6. A textile ring having an upper rim adapted to be embraced by the upper hook of a traveler and a lower rim adapted to be embraced by the lower hook of a traveler, said ring having a reentrant lubricant channel opening into the inner face of said ring, an imperforate liner mounted in said channel, said liner having a thickness less than the depth of the channel to provide a chamber in back of said liner, a tubular wick in said chamber substantially filling the same and being in contact with said liner, a lubricant reservoir formed integrally with said ring and extending circumferentially around the exterior of said ring, said ring having a bore leading from said chamber in back of said liner to said reservoir, wick means extending through said bore having one end thereof in the lubricant of said reservoir and the other end thereof in communication with said tubular wick contained in said chamber in back of said liner, said wick means providing a constant lubricant supply to said tubular wick contained in said chamber in back of said liner, and means on said traveler for engaging with said liner being operable to movably actuate the same and cause said tubular wick to provide a supply of lubricant to said traveler.

7. The combination of claim 6 wherein said lubricant reservoir is provided with a segmental portion which is divided from the remainder of said lubricant reservoir, a packing contained in said segmental portion, and a feeder wick having one end portion thereof extending into said free lubricant and the other end thereof in engagement with said packing.

8. A textile ring adapted to be embraced by a traveler, said ring having a reentrant lubricant channel opening into the inner face of said ring, a liner mounted in said channel, said liner having an inner diameter somewhat larger than the inner diameter of said ring, said liner having a thickness less than the depth of the channel to provide a chamber therebetween, lubricating means in said chamber, a lubricant reservoir formed integrally with said ring and extending circumferentially around the exterior of said ring, lubricating means contained within said reservoir, means associated with said second named lubricating means and communicating between said reservoir and said lubricating means in said chamber, effec-

tive to supply a lubricant to the latter, said traveler being operable to actuate said liner and condition the lubricating means in said chamber to provide a supply of lubricant to said traveler.

9. A textile ring adapted to be embraced by a traveler, said ring having a reentrant lubricant channel opening into the inner face of said ring, an imperforate liner mounted in said channel, said imperforate liner having an inner diameter somewhat larger than the inner diameter of said ring, said liner having a thickness less than the depth of the channel to provide a chamber therebetween, a lubricant reservoir formed integrally with said ring and extending circumferentially around the exterior of said ring, means communicating between said reservoir and said chamber, being effective to provide lubricant to said chamber, and means in said chamber responsive to an actuation of said liner to said traveler to provide a supply of lubricant to the latter.

10. A textile ring having an upper rim adapted to be embraced by the upper hook of a traveler and a lower rim adapted to be embraced by the lower hook of a traveler, said ring having a reentrant lubricant channel opening into the inner face of said ring, an imperforate liner mounted in said channel, said liner having a thickness less than the depth of the channel to provide a chamber therebetween, a tubular wick in said chamber, a lubricant reservoir on said ring, a packing contained within said reservoir, a feeder wick associated with said packing and communicating between said packing and said reservoir, a supply wick communicating between said packing and said tubular wick in said chamber, said feeder and supply wicks providing constant lubricant supply to said tubular wick contained in said chamber in back of said liner.

11. A textile ring having an upper rim adapted to be embraced by the upper hook of a traveler and a lower rim adapted to be embraced by the lower hook of a traveler, said ring having a channel opening on the inner face of said ring, a liner mounted in said channel, a lubricant absorbing wick in said channel behind said liner, said upper rim having a radius greater than said lower rim, the radial center of said lower rim being outside of the radial center of said upper rim, said traveler having a shank portion connecting said upper and lower hook portions, whereby during use a portion of said shank is caused to contact said liner, said liner in turn squeezing said absorbing wick contained in said channel thereby releasing lubricant, the quantity of which is determined in part by the speed of said traveler.

12. A textile ring having an upper rim adapted to be embraced by the upper hook of a traveler and a lower rim adapted to be embraced by the lower hook of a traveler, said ring having a channel opening on the inner face of said ring, a liner mounted in said channel, a lubricant absorbing wick in said channel behind said liner, said upper rim having a radius greater than said lower rim, the radial center of said lower rim being outside of the radial center of said upper rim, said upper rim having substantially vertical parallel extending sides, said lower rim having converging sides to provide a relatively narrow contact area with the lower hook portion of said traveler, said traveler having a shank portion connecting said upper and lower hook portions, said shank portion having a bend therein substantially adjacent said lower hook portion, said upper hook portion engaging said upper rim in point contact, said lower hook portion engaging said lower rim portion in point contact, said bend in said shank portion adapted to engage said ring in point contact, whereby said upper hook portion of said traveler is caused to tilt radially inwardly of said ring during use, and centrifugal force causing the central shank portion thereof to flex radially outwardly into contact with said liner, said liner thereby squeezing said tubular wick contained in said channel thereby releasing lubricant, the quantity of which is determined by the speed of said traveler.

13. A textile ring having an upper rim adapted to be embraced by the upper hook of a traveler and a lower rim adapted to be embraced by the lower hook of a traveler, said ring having a channel opening on the inner face of said ring, a liner mounted in said channel, a lubricant absorbing wick in said channel behind said liner, said upper rim having a radius greater than said lower rim, said traveler having a shank portion connecting said upper and lower hook portions, said shank portion having a bend therein substantially adjacent said lower hook portion, said bend in said shank portion adapted to engage said ring in point contact, whereby a portion of the shank is caused to flex radially outwardly during use into contact with said liner, said liner thereby squeezing said tubular wick contained in said channel thereby releasing lubricant, the quantity of which is determined by the speed of said traveler.

14. In combination, an elongated horizontally disposed textile rail having a ring opening therein, a textile ring adapted to be associated with said ring opening, said ring having a lubricant channel formed therein opening toward the inner face of said ring, an imperforate bearing liner in said channel, the inner face of said bearing liner disposed within said channel and forming offset shoulders with the inner face of said ring, a tubular wick in said channel substantially filling the same and being in contact with said liner, a lubricant reservoir integrally associated with said ring, said lubricant reservoir extending circumferentially around the outer periphery of said ring, a packing contained within said reservoir, wick means associated with said packing and communicating between said reservoir and said tubular wick in said channel, means associated with said ring whereby said ring is mounted above the plane of said textile rail.

15. In combination, an elongated horizontally disposed textile rail having a plurality of ring openings therein, a plurality of textile rings one of which is adapted to be associated with each of said ring openings, each of said rings having a lubricant channel formed therein opening toward the inner face of said rings, an imperforate bearing liner in said channel, the inner face of said bearing liner contained within said channel and forming offset shoulders with the inner face of said ring, a lubricant reservoir integrally associated with each of said rings, said lubricant reservoir extending circumferentially around the outer periphery of each of said rings, a conduit extending laterally and downwardly from said channel to said lubricant reservoir, means for transmitting said lubricant from said lubricant reservoir to said channel, mounting means associated with each of said rings whereby said rings are mounted in their entirety above the plane of said textile rail.

16. The combination of claim 15 wherein said mounting means associated with each of said rings comprise a mechanical fastener and spacer means which are adapted to engage said rail adjacent the outer periphery of said ring openings.

17. In combination, an elongated horizontally disposed textile rail having a ring opening therein, a textile ring, said textile ring adapted to be associated with said ring opening, said ring having a lubricant channel formed therein opening toward the inner face of said ring, an imperforate bearing liner in said channel, and a lubricant reservoir integrally associated with said ring, said lubricant reservoir extending circumferentially around the outer periphery of said ring and lubricant absorbing means communicating lubricant between said reservoir and said channel, said absorbing means being responsive to an actuation of said bearing liner by said traveler to provide a supply of lubricant to the same.

18. The combination of claim 17 wherein said lubricant reservoir is provided with a segmental portion divided from the remainder of said lubricant reservoir, packing contained in said segmental portion, the remainder of said reservoir containing free lubricant, a feeder wick

communicating between said packing and said free lubricant in said reservoir.

19. A textile ring having rim surfaces for engagement with a traveler, a lubricant reservoir in said ring opening to the inner face of the same and operable to store a quantity of lubricant therein, means in said reservoir defining pump means including an imperforate liner engageable with said traveler and operable by the latter to slidably move within said reservoir, and diaphragm means disposed in said reservoir being actuatable in response to 10

the movement of said liner to cause a predetermined amount of lubricant to be supplied to said rim surfaces.
